UNITED STATES PATENT OFFICE.

JOSEPH A. SCHMITZ, OF CHICAGO, AND ADYN E. SCHUYLER, OF EVANSTON, ILLINOIS.

GRAIN DOOR FOR FREIGHT CARS.

Application filed April 19, 1924. Serial No. 707,573.

To all whom it may concern:

Be it known that we, JOSEPH A. SCHMITZ and ADYN E. SCHUYLER, citizens of the United States, residing, respectively, at Chicago, in the county of Cook and State of Illinois, and at Evanston, in the county of Cook and State of Illinois, have invented certain new and useful Improvements in Grain Doors for Freight Cars, of which the following is a specification.

Our invention relates to a device which we have invented for forming a closure for the door opening of box cars and is particularly adapted for use in shipping grain. It is now the practice to employ for this purpose standard door sections made according to various specifications adopted by the different railroad companies, these doors being supplied to shippers by the railroads. The sections are uniformly seven feet in length and twenty inches in width, and are frequently constructed of two thicknesses of lumber making broken joints, the boards on one side being shorter than the other to provide for a cross-piece at each end of the section of the same thickness as the other boards at that side, these cross-pieces being designed to be placed facing the inside of the car when the section is in use, as in the typical door illustrated in the drawing. As ordinarily used, these door sections are simply nailed across the door opening, one above another, from three to five sections being employed, sometimes three sections being used, as illustrated, and often four, and less frequently five.

In unloading cars thus loaded with grain, it is the common practice to remove the top door first; then the next lowermost, etc., in succession, as the grain level is lowered in the car. As the grain is compacted by the jarring to which the car is subjected in transportation, particularly the lower layers of the grain, it is by no means an easy matter to remove the doors. This is done, when a car has been properly loaded, by forcing the ends of the door inwardly by heavy pointed iron bars against the pressure of the grain to unseat the nails, and then forcing the doors upwardly. The second door from the bottom is usually especially hard to dislodge. In some cases, where the shipper has ignorantly applied a reinforcement inside the closure connecting two doors it is sometimes necessary to chop an opening

in the bottom door to let the grain flow out at that point to the unloading hoppers. In any case the doors are liable to be subjected to very rough treatment in removing them, and are frequently so broken or damaged as to be no longer serviceable.

Since the door sections are removed one by one, the flow of the grain proceeds by stages, and as a number of cars, frequently five or six, are simultaneously unloaded at one long platform, an interruption of the unloading operation, due, it may be to improper closure of one of the cars, results in delay to all the others.

In our pending application for patent filed July 13, 1923, Serial No. 651,236, we have described and claimed a grain door having a destructible and replaceable bottom closure together with an associated bracing bar adapted to serve as an implement by which to wreck the closure member, and the present invention may be regarded as an improvement upon and a modification of the device shown in that application.

The principal objects of our present invention are to provide a destructible closure member of novel construction better adapted to serve the purposes for which it was designed than any hitherto known to us, and to provide a supporting bar member of novel arrangement with respect to the standard door sections, whereby a more desirable grain door closure is provided than has heretofore been possible. With these objects in view we have devised and invented the car closure hereinafter described, and the essential elements of our invention being more particularly set forth in the appended claims.

In the accompanying drawings we have illustrated our invention in a preferred form, and also in a modified form of embodiment. Figure 1 is a side elevation of a portion of a box car showing our invention in its preferred form applied thereto; Fig. 2 is a view of the same viewed from inside the car; Fig. 3 is a vertical section on the line 3—3 of Fig. 1; Fig. 4 is an enlarged detail showing in vertical section the lower end of the wrench bar and connected parts; and Fig. 5 is a top plan view of the destructible closure member, detached and drawn to a relatively small scale; Figs. 6 to 10 illustrate a modified form of our invention, the figures numbered 6, 7, 8 and 9 correspond-

ing respectively to Figs. 1, 2, 3 and 5, and Fig. 10 being a top plan view of the entire closure and adjacent portions of the frame of the car.

As hereinbefore stated, the member of the car door to which our invention more particularly relates includes the destructible bottom closure which is of composite or built-up construction and is made of two end sections 1 and 2 and a middle section 3 united by a splicing section 4 which is nailed to the other sections on their outer sides. The sections 1, 2 and 3 may be formed of relatively thin pieces of board, and the sections are all of suitable uniform width to form a closure member which preferably is about eight inches high, though this may vary somewhat. The ends of this closure member are nailed lightly to the posts at the side of the door opening, on the inside of the car, and above this the door sections, of ordinary construction, are nailed in the usual manner. In the present instance, we have illustrated three sections marked A, B and C, though more may be used if desired.

On the outer face of the bottom closure member are arranged two inclined wrench bars 5 and 6 which are secured to the closure member opposite the end portions of its middle section 3 by means of bolts 7 and 8, respectively. The bars 5 and 6 are of such materials and dimensions as to possess considerable strength and stiffness, and are each anchored to the floor of the car by means of a flat anchorage strip of metal 9, one end of which engages the lower prong of a strong U-shaped staple 10 driven into the bar at its lower end, and the other end of which is carried inside the car and nailed to the floor. The staple is of heavy construction and rounded between its prongs, and preferably the prongs are blunt and adapted to be driven into previously formed holes of the proper size to make a tight fit. The pivotal connection of the strip with one prong only of the staple enables the strip to be seated flat against the floor whatever the inclination of the bar and whatever irregularity there may be in the floor. Ready detachment of the bars 5 and 6 from the anchorage strips by a suitable pointed iron bar or other implement which is of great practical importance is provided for in this manner. The strips 9 may be formed of box strapping of suitable weight (say about 18 gauge) though wire may be employed if desired.

At the upper end of each bar, which is of such length that its top will extend to a point opposite the upper edge of the second or third door section, in the present instance the second, a doubled strip of metal 11, which may be formed of the same material as the strips 9, is connected to the bar

through engagement with the upper prong of a staple 12 similar to the staples 10 before mentioned. In applying the closure the free ends of the strip are passed over the top of the adjacent section lying below the top of the bar and are bent downwardly and fastened to such section, or, if desired, the upper fold of the strip may be bent upwardly and fastened to such upper section and the lower fold nailed to the section below, as shown in Fig. 3. If desired, the member 11 may be formed of wire, though a flat strip of box strapping is more suitable and more readily applied.

It will be observed that if all the parts are accurately made and true in form, there will be a gap between the bars 5 and 6 and the door sections, which gap at the bottom is the width of the thickness of the splicing section 4. This, however, is an advantage, since the grain has a tendency to flow in a manner similar to that of a liquid under fluid pressure, and the weight of the grain presses the door sections outwardly when the car is loaded. The stratum of grain next the floor, however, is retarded by the friction between the floor and the grain immediately above it, so that the greatest side-wise pressure is not exerted against the closure member, but against the lowermost door section. As the pressure on this lower section is greatest, it will spring the most and the other sections successively less from the bottom towards the top, and the thickness of the splicing section is such that in a loaded car the outer faces of the sections will all bring up against the bars 5 and 6, individually taking up a considerable portion of the strain before they do so.

In applying the closure, the anchorage strips 9 are drawn snug in nailing them to the floor, so that the closure member below the doors will be permitted little or no outward movement. Since the tops of the inclined bars 5 and 6 are secured to the top of the upper door section near opposite ends of such section and near where the section bears against the posts at the sides of the car opening, the springing of the doors in the manner described will evidently result in an approximately equal distribution of the pressure of the grain along the bars and between the side posts and floor of the car. To open the door the bottom closure strip, consisting of the end members 1, 2 and the splicing strip 4, is first wrecked or torn away. This is accomplished by releasing the upper ends of the bars 5, 6, the securing ends of which are detachable from the anchoring boards by inserting a blade such as that of a chisel beneath the upper ends of the members 5, 6 and prying the folded strips 11 loose, the tacks by which the ends of the latter are secured readily yielding and the strap bending to permit it to be with-

drawn. The upper ends of the bars are then pulled outward, as shown in dotted lines in Fig. 3, the splicing strip being so firmly secured thereto that it tilts outward with the bars and is torn away from the end strips 1, 2 to which it is nailed. The flexible connection to the strap 9 permits the bars to swing outward as described. After the composite bottom strip has been ruptured in this manner it is readily removed from the door-way.

Describing now the modified form of our invention shown in Figs. 6 to 10, the 15 de-
structible closure member 1 is of composite
or built-up construction quite similar to that
above described and includes three inner
sections, a short end section 13, an intermediate
section 14, and a long end section 15, united
20 by an outer splicing section 16, which
overlaps the two end sections on opposite
sides of the intermediate section. The sections
13, 14 and 15 are formed of relatively
thin board, and all the sections are of uniform
25 width to form a closure member of the
desired size. The sections may be conveniently
secured together by nails and the
ends of the closure member are lightly
nailed to the posts at the side of the door
30 opening on the inside of the car, as in the
preferred form before described, and above
the destructible closure member the door sections
are nailed to the posts in the usual manner.

Pivottally secured to the closure member
35 by a bolt passing through the sections 14
and 16 is a wrench bar 17 of adequate stiffness
and strength. This wrench bar extends
from its lower end diagonally across the center
40 line of the car door sections to the post
on the opposite side, to which it is firmly
secured in a suitable manner, as by means of
a piece of box strapping 18 passing around
its end and nailed to the post.

The lower end of the wrench bar is
45 anchored to the floor of the car by means of
a strip of sheet metal 19, one end of which
engages the lower prong of a strong U-
shaped staple 20 driven into the bar at its
50 lower end and the other end of which is
carried inside the car and nailed to the floor.

When the grain is to be unloaded the
55 staples 10 (or 20, as the case may be) are
withdrawn by a suitable tool, and the bars
5 and 6 (or the bar 17) employed as wrench
bars to break away the center portion of the
closure member, the composite construction
60 described facilitating such operation. The
intermediate closure section nailed to the
splicing section and both bolted to the wrench
bars forms a strong rugged central block
which can readily be detached from the end
portions, thus wrecking the closure member.

In this manner an opening is provided at the
bottom of the closure through which the

grain may flow, and as the grain is removed
the upper, intermediate and lower door sections
are taken down in order.

After the car is unloaded the anchoring
strips 9 and 11 (or 19 and 18) may be re-
moved, and if serviceable reconnected by
means of the staples 10 with the wrench
bars 5 and 6 (or the bar 17, as the case may
be) and the closure member repaired or
replaced, so that it may be used again. Ob-
viously the provision of the destructible
bottom closure member increases the capac-
ity of the car to the extent of its height, and
this advantage is attained by means of a
relatively cheap and light member which
can be repaired or replaced at slight expense
after being used.

In the drawings illustrating the preferred
form of our invention the wrench bars are
secured to the destructible closure member
at points somewhat nearer the center of the
door opening than the sides, and spread up-
wardly to points on the joint between the
second and third door sections adjacent the
sides of the door opening. The points of
attachment of the bars and their inclination
may of course be varied somewhat, and the
upper ends of the bars may extend to the
car frame at the sides of the door opening
and be directly connected thereto, in the
same manner as the modified form of our
invention above described, (see Fig. 6) in-
stead of being indirectly connected through
an upper door section, as illustrated in Fig.

1. In this case the wrench bars would prefer-
ably be secured to the destructible closure
member near its center and the upper ends
of the bars extend to about the top of the
uppermost door section.

In place of the U-shaped staple 10 (or
20) above mentioned, a pin driven into a
socket to make a tight fit may be employed,
and an ordinary split cotter pin having a
looped head is excellently adapted for the
purpose, since the spring of the halves of
the pin may be utilized to cause a secure en-
gagement and the loop of the head provides
for ready detachment,—see this alternative
construction illustrated at the bottom of
Fig. 8.

We claim:

1. The combination of a lower de-
structible closure member for a car closure which
includes horizontal door sections, said mem-
ber including an intermediate splicing sec-
tion and lapping end sections lightly se-
cured to said intermediate section, and an
exterior upwardly extending wrench bar
secured to said splicing section, said wrench
bar being detachably anchored to the car
floor and detachably connected at its upper
end with the car frame adjacent the side of
the door opening.

2. The combination of a lower de-
structible closure member for a car closure which

- includes horizontal door sections, said member including an intermediate splicing section and lapping end sections lightly secured to said intermediate section, and an exterior upwardly extending wrench bar secured to said splicing section, said wrench bar being anchored to the car floor and secured at its upper end against said door section.
10. 3. The combination of a lower destructible closure member for a car closure which includes horizontal door sections, said member including an intermediate splicing section and lapping end sections lightly secured to said intermediate section, and an inclined wrench bar detachably anchored to the car floor at the bottom and secured to said intermediate section, said bar extending upwardly towards the sides of the door opening and being detachably connected at its upper end with the car frame adjacent the side of the door opening.
4. The combination of a lower destructible member for a car closure which includes horizontal door sections, said member including inner end sections having their outer faces arranged to lie in the same plane as the outer faces of the door sections, and also including an outer splicing section lightly secured to said end sections and lying outside of said plane, and an upwardly extending wrench bar having an inner plane face contiguous to the outer face of the splicing section and secured thereto at its bottom end, said wrench bar being detachably anchored to the car floor and connected at its top to the car frame adjacent the side of the door opening.
5. The combination of a lower destructible member for a car closure which includes horizontal door sections, and an upwardly inclined wrench bar secured to said destructible member and having a plane inner face spaced away from the door sections a distance less than their normal outward spring under grain pressure, said member being anchored to the car floor and connected at its top to the car frame adjacent the side of the door opening.
6. The combination of a lower destructible closure member for a car closure which includes horizontal door sections, and an exterior upwardly-extending wrench bar secured to said destructible member and having a plane inner face spaced away from the door sections a distance less than their normal outward spring under grain pressure, said member being anchored to the car floor and secured at its upper end.
7. The combination of a lower destructible member for a car closure which includes horizontal door sections, said destructible member including an outer member extending outside the plane of the door sections, and an upwardly extending wrench bar secured to said destructible member and having an inner face plane spaced away from the door sections a distance less than their normal outward spring under grain pressure and said member being anchored to the car floor and connected at its top to the car frame adjacent the side of the door opening.
8. In a car door closure including horizontal door sections and a destructible bottom closure member and a wrench bar secured thereto and having connection at its top with the car frame adjacent the side of the door opening, means for detachably anchoring the lower end of said bar to the floor comprising a U-shaped staple frictionally engaging sockets in said bar and a strip of sheet metal engaging one prong of said staple and adapted to be nailed to the car floor.
9. A closure for a car door opening extending horizontally across said opening and overlapping and lying against the inner faces of the posts at the sides of said opening, a bar inclining upwardly from the floor of the car upon the outer side of said closure to a point adjacent one of the posts at the sides of said door opening, an anchor member extending from the lower end part of said bar beneath said closure to the inside of said car, means securing said anchor member to said bar and to the floor of the car inside of said closure and means for securing the upper end of said bar to said post.
10. A closure for a car door opening extending horizontally across said opening and overlapping and lying against the inner faces of the posts at the sides of said opening, said closure comprising a lower section having a central member and end members, said end members partially overlapping and lying against the inner side of the extremities of said central member, a bar secured to said central member and extending upwardly from the floor of the car upon the outer side of said closure, means securing the lower end of said bar to the floor of the car and means securing the upper end of said bar against outward movement.
11. A closure for a car door opening extending horizontally across said opening and overlapping and lying against the inner faces of the posts at the sides of said opening, said closure comprising a lower section having a central member and end members, said end members partially overlapping and lying against the inner side of the extremities of said central member, a bar secured to said central member and extending upwardly from the floor of the car upon the outer side of said closure, an anchor extending from the lower end part of said bar beneath said lower section to the inside of the car, means securing said anchor member to said bar and to the floor of the car inside.

of said closure and means for securing the upper end of said bar against outward movement.

12. A closure for a car door opening extending horizontally across said opening and overlapping and lying against the inner faces of the posts at the sides of said opening, said closure comprising a lower section having a central member and end members, 5 said end members partially overlapping and lying against the inner side of the extremities of said central member, a bar inclining upwardly from the floor of the car upon the outer side of said closure to a point adjacent 10 one of the posts at the sides of the door opening, means securing the lower end of said bar to said central member and to the floor of the car and means securing the upper end of the bar to said post.

20 13. A closure for a car door opening extending horizontally across said opening and overlapping and lying against the inner faces of the posts at the sides of said opening, said closure comprising a lower section having a central member and end members, 25 said end members partially overlapping and lying against the inner side of the extremities of said central member, a bar inclining upwardly from the floor of the car upon the outer side of said closure to a point adjacent 30 one of the posts at the sides of the door opening, means securing the lower end of said bar to said central member and to the floor of the car, and means securing the upper end of said bar against outward movement.

35 14. A closure for a car door opening extending horizontally across said opening and overlapping and lying against the inner 40 faces of the posts at the sides of said opening,

ing, said closure comprising a lower section having a central member and end members, said end members partially overlapping and lying against the inner side of the extremities of said central member, a bar inclining upwardly from the floor of the car upon the outer side of said closure to a point adjacent one of the posts at the sides of the door opening, means securing the lower end of said bar to said central member, an anchor member extending from the lower end part of said bar beneath said lower section to the inside of said car, means securing said anchor member to said bar and to the floor of the car inside of said closure, 45 and means for securing the upper end of said bar against outward movement.

50 15. A closure for a car door opening extending horizontally across said opening and overlapping and lying against the inner faces of the posts at the sides of said opening, said closure comprising a lower section having a central member and end members, 55 said end members partially overlapping and lying against the inner side of the extremities of said central member, a bar inclining upwardly from the floor of the car upon the outer side of said closure to a point adjacent one of the posts at the sides of the door opening, means securing the lower end of 60 said bar to said central member, an anchor member extending from the lower end part of said bar beneath said lower section to the inside of said car, means securing said anchor member to said bar and to the floor of 65 the car inside of said closure, and means securing the upper end of said bar to said post.
